REFINING OF PETROLEUM OILS

Henry C. Paulsen, Elizabeth, N. J., assignor to
Standard Oil Development Company, a corpora-
tion of Delaware

Application December 30, 1941, Serial No. 424,856

6 Claims. (Cl. 196—33)

This invention is concerned with a method of treating petroleum oils to remove suspended lead sulfide from doctor sweetened stocks. It is particularly applicable for effective removal of minor traces of lead sulfide remaining suspended in light petroleum distillates following a doctor sweetening operation as an improvement over the common practice of water washing.

The doctor sweetening process involves the formation of lead sulfide which, due to its finely divided state, settles very slowly after the product is sweetened to a low reactive sulfur content. Customarily, a final water washing operation is employed to free the sweetened oil of remaining suspended lead sulfide after most of the lead sulfide formed is separated by settling from the treated oil, in order to prevent excessive lead losses and to recover a clear sweetened product as free as possible of lead sulfide. This water washing procedure has been found inefficient in removing the final traces of suspended lead sulfide with practical limitations of time, apparatus, and amount of washing water, resulting in excessive lead losses, and thus the lead sulfide remaining in the sweetened stocks tends to settle out in refinery tanks and necessitates periodic cleaning.

In accordance with the present invention, it has been found that the doctor sweetened petroleum stocks containing suspended lead sulfide may be effectively freed of lead sulfide by washing the sweetened stocks with aqueous solutions of salts of thiazole compounds, preferably alkali metal salts of mercaptoaryl thiazole compounds, such as the sodium salt of mercapto benzo-thiazole and its related derivatives. Accordingly, the preferred thiazole salts contain the characteristic meta thiazole function

in a heterocyclic compound represented by the formula $Ar(NSC)SM$, wherein Ar represents an arylene radical, such as the phenylene radical (C_6H_4) or a substituted benzene ring with sulfur and nitrogen attached to ortho carbon atoms in the aromatic nucleus and linked to the metal constituent M through carbon and sulfur, as shown in the following structure:

The following examples present results ob-

tained by washing a doctor sweetened gasoline with aqueous solutions of sodium salt of mercapto-benzothiazole and with other solutions:

Example

5 Gasoline from a doctor sweetening plant obtained at the outlet of the second doctor settling drum was treated with 10% by volume of the washing solution with one minute of agitation.

10 The sweetened gasoline after only water washing and paper filtering had a copper dish gum of 3 and a sulfur content of 0.092%, while a similar portion of the same gasoline, after being treated with 10% by volume of sodium salt of mercapto-benzothiazole solution in which the concentration of the mercapto-benzothiazole salt was 10 mg./100 ml. for lead sulfide removal, followed by paper filtering, had a copper dish gum of only 2 and a sulfur content of 0.086%.

15 20 In addition to the above-described operation, a portion of the mercapto-benzothiazole salt solution (10 mg./100 ml.) was recirculated forty times on portions of the above gasoline to substantially free it of lead sulfide. After the forty recirculation cycles, the washing solution was found to be as effective in removing lead sulfide from the gasoline as it was in the initial cycle.

25 30 In using the more effective thiazole salt washing solutions for lead sulfide removal from sweetened stocks, the plant procedure may be efficiently carried out by charging the wash drum with about 2000 gallons of said washing solution and recirculating the washing solution with small additions of fresh solution to replace the small portion rendered ineffective or lost. The precipitated lead sulfide which is effectively removed by the washing solution may be readily separated by draw-off in a settler and/or a centrifuging operation to be returned to a regenerator 35 40 in the doctor treating system.

45 In the accompanying drawing is shown a flow diagrammatic view of a typical and suitable plant set-up for the doctor sweetening and washing operations.

50 55 In the drawing, numeral 1 indicates a feed inlet line for the sour gasoline or light petroleum stock containing mercaptans, which is to be subjected to doctor sweetening, said stock having incorporated the necessary amount of added free sulfur for the treatment. The sour distillate is passed by pump 2 through line 3 into the orifice mixer 4 wherein it is intimately mixed with doctor solution, led into line 3 from line 5 by pump 6. The orifice mixer is equipped internally with orifices 7 at spaced points for obtaining agita-

tion and intimate mixing. From the orifice mixer, the doctor sweetening reaction mixture is led by line 8 to the settler 9 wherein spent doctor reagent is settled to the bottom to be withdrawn through line 10 and control valve 11 to outlet line 12. For further removal of spent doctor reagent, the sweetening reaction mixture is led from the first settler 9 through line 13 into a second settler 14 wherein the settling operation is repeated, all of the settled doctor reagent being removed from the settler through line 15 and control valve 16 to be withdrawn from the system by line 12, which may be used to transfer the spent doctor solution to a sodium plumbite regenerating unit (not shown). It is to be understood that the described part of the doctor sweetening operation may be carried out in units of various forms, such as are conventional or otherwise.

The sweetened oil, following the separation of the spent doctor reagent with the major part of the lead sulfide, still retains a certain small amount of finely divided lead sulfide in suspension. This product is passed from the final settling zone to the washing unit, as illustrated in the drawing, by being led from the second settler 14 through line 17 into an orifice mixer 18, to which is simultaneously fed the washing liquid or solution from inlet line 21 by pump 22 and a desired amount of recirculated or used washing liquid from line 23. The mixture of the doctor sweetened oil and washing solution is discharged from the mixer via line 19 into a settler 20, wherein the washing solution and lead sulfide is settled to the bottom, and the sweetened hydrocarbon oil substantially freed of lead sulfide is withdrawn from an upper stratum through line 24. The settled aqueous layer is withdrawn from the bottom of settler 20 through line 25, and any amount thereof may be led through valve 26 into line 23 for recirculation, as mentioned. Any portion of the withdrawn settled aqueous

in the lead sulfide separation is very small, being of the order of from about 0.005% to 0.1% by weight and preferably in the range of 0.01% to 0.08% (from about 10 mg. to 80 mg./100 ml. of aqueous solution).

There are a number of modifications which may be made in the thiazole salt composition used in accordance with the present invention, as, for example, in the selection of the organic radical bonded to the thiazole function and the cation or metallic constituent. For example, substituted aromatic hydrocarbon radicals may take the place of the phenylene radical, e. g., nitro, halogen, alkyl, oxy, or hydroxy groups may be substituents in the aromatic nucleus. In the place of sodium, other metals, preferably base metals, may be used, e. g., potassium, ammonium radical, or alkaline earth metals. However, it is desirable to restrict the oil-solubility of the salts for the present purposes, and it is preferred that the salts be substantially insoluble in the hydrocarbon oil yet soluble in water.

The thiazole salt settling agents herein described may be used in various modifications of the doctor treatment. They may be used where sweetening is conducted in a batch system or in a continuous procedure, as described. They may be employed to obtain more rapid and complete separation of the suspended metal sulfide when lead sulfide is used by itself as a sweetening agent, or with some other metal compound. It has been found that the thiazole salt agents are beneficial in obtaining a neutral finished distillate satisfactorily free of lead sulfide, having a very good appearance and with a desirable reduction in sulfur content and even of gum-forming constituents.

Tests have further demonstrated that in addition to accelerating the separation and shortening the settling period, the thiazole salt solutions are superior to other types of aqueous solutions commonly employed as is illustrated in the following test data:

Reagents	Fresh water	Salt water	Aqueous solution of 3° Bé NaOH	Aqueous solution of 10° Bé NaOH	Sodium salt of mercapto-benzothiazole solutions			
					5 mg. per 100 ml.	10 mg. per 100 ml.	20 mg. per 100 ml.	80 mg. per 100 ml.
Settling rate in seconds.	10.	10.	9.	8.	8.	7.	7.	6.
Separation.	Poor.	Poor.	Poor.	Fair.	Good.	Very good.	Very good.	Fair.
Appearance of oil.	PbS present.	PbS present.	PbS present.	Slight PbS present.	PbS free.	PbS free.	PbS free.	PbS free.
PbS crawl on side of bottle.	Heavy.	Heavy.	Heavy.	Heavy.	Very silt.	None.	None.	Slight.

¹ PbS was in a coagulated form.

solution may be led by line 25 through opened valve 27 into a suitable unit for separation and recovery of lead sulfide from the aqueous solution, and the thus recovered lead sulfide may be used for regeneration into sodium plumbite, or doctor reagent.

In the described plant operation, the desired concentration of thiazole salt is maintained in the washing solution by addition of the necessary amount of the salt to the fresh water charged into the washing unit through line 21.

In general, the washing treatment is carried out in the vicinity of atmospheric pressure or under slightly elevated pressures ranging up to about 30 lbs./sq. in. gauge and under moderate temperatures varying from about 30° F. to 120° F., which is mainly dependent upon atmospheric conditions.

The amount of the thiazole salt which may be recommended for use in the aqueous washing solution for making a considerable improvement

55 I claim:

1. In a process of sweetening a hydrocarbon distillate oil containing mercaptans following the dispersion of finely divided metal sulfides in the sweetened distillate product, the step comprising separating said metal sulfides from the oil by washing with an aqueous solution containing a small concentration of a mercapto-aryl thiazole salt of a substance selected from the group consisting of alkali metals, alkaline earth metals and the ammonium radical which is substantially insoluble in the hydrocarbon oil.

2. In the process of sweetening a hydrocarbon distillate oil by a doctor treating agent, the step of removing final traces of lead sulfide from the doctor sweetened oil consisting in washing the sweetened oil with water containing in small concentration an alkali metal salt of a mercapto-arylthiazole.

3. In the process of sweetening a sour petroleum distillate by a doctor solution of alkaline

sodium plumbite, the step of removing the final traces of lead sulfide from the sweetened oil which comprises washing the sweetened oil with water containing about 0.005% to about 0.1% by weight of the sodium salt of mercaptobenzo-thiazole.

4. In the process of sweetening a sour petroleum oil by a doctor treating agent, the improvement in the step of washing following removal of spent doctor treating agent from the sweetened oil to remove final traces of suspended lead sulfide which comprises adding to water used in the washing a small amount of a mercapto-aryl thiazole salt the cation of which forms hydroxides soluble in water.

5. In the process of sweetening a sour hydro-

carbon distillate by a doctor solution of alkaline sodium plumbite, the step of removing the final traces of lead sulfide from the sweetened oil which comprises washing the sweetened oil with water containing about 0.005% to about 0.1% by weight of the potassium salt of mercapto-benzo-thiazole.

6. In the process of sweetening a sour hydrocarbon distillate by a doctor solution of alkaline sodium plumbite, the step of removing the final traces of lead sulfide from the sweetened oil which comprises washing the sweetened oil with water containing about 0.005% to about 0.1% by weight of the ammonium salt of mercapto-benzo-thiazole.

HENRY C. PAULSEN.
